UNITED STATES PATENT OFFICE.

LEON A. NORTHRUP, OF SAN FRANCISCO, CALIFORNIA.

ALARM SYSTEM.

1,121,124.

Specification of Letters Patent.

Patented Dec. 15, 1914.

Application filed October 14, 1912. Serial No. 725,642.

To all whom it may concern:

Be it known that I, LEON A. NORTHRUP, a citizen of the United States, residing at the city and county of San Francisco and State of California, have invented new and useful improvements in Alarm Systems, of which the following is a specification.

This invention relates to an alarm or signal apparatus.

10 It is the object of this invention to provide an apparatus for giving a signal to denote that unauthorized entrance has been made to buildings, vaults, cabinets or other inclosed structures, and which is particularly adapted for use as a burglar alarm.

Another object is to provide a device of the above character which is simple in construction, efficient and reliable in operation, and inexpensive to install.

20 A further object is to provide an alarm system in which the electric current is employed in blowing a whistle and producing a light, thus giving a signal which can be recognized by the sense of sight and the sense of hearing.

Other objects will appear hereinafter.

The invention primarily resides in disposing a whistle and an electric light at any convenient point, providing means operated by a motor for creating a current of air to sound the whistle, with means controlled by the motor for flashing the light intermittently, and in providing electrical connections whereby the opening of a door, window, or other closure will act to set the motor in operation and thereby turn on the light and blow the whistle.

The invention further consists of the parts and the construction and combination of 40 parts as hereinafter more fully described and claimed, having reference to the accompanying drawings, in which—

Figure 1 is a longitudinal section of the invention showing the electrical connections in diagram. Fig. 2 is a transverse section of the invention partly in elevation.

In the drawings A represents a case or cabinet of any suitable construction in which a crank shaft 2 is revolvably mounted. A 50 wheel 3 is mounted on the crank shaft 2 and is connected by means of a belt or chain 4 to a driving wheel 5 on the shaft 6 of an electric motor 7, of any suitable description; the crank shaft 2 being designed to be driven 55 from the motor 7 when the latter is in opera-

tion. Connected to the crank of the crank shaft 2 is a series of pitman rods 8, the outer ends of which connect to bellows 9 of any suitable construction mounted on the interior of the case A.

60 The bellows 9 are fitted with the usual valved inlet openings 10 and valved outlet openings 11; the latter leading to a continuous passage 12 formed in the case A and communicating with each of the bellows 9. 65 Connecting with the passage 12 is a conduit or pipe 13 which leads to one or more whistles 14 of any suitable description, disposed at any convenient point.

70 Mounted on the crank shaft 2 is a cam 15 which is designed, when the cam is rotated, to actuate an arm 16 pivoted at 17, and normally held in contact with the outer face of the cam by means of a spring 18. The arm 16 is formed with a contact member 75 19 on its outer end which is adapted to be thrown in and out of contact with a contact member 20 on an arm 21 when the cam 15 is rotated to make and break an electrical circuit leading from a battery B to one or 80 more electric lights 22 disposed at any convenient point.

75 The arm 21 is pivoted at 23 and has its movement toward the arm 16 limited by means of a stop 24; a spring 25 acting to 85 hold the arm 21 in its normal position in which the contact member 20 will be spaced a short distance from the contact member 19. This construction admits of the arm 21 moving upward in unison with the arm 16 90 when the latter is brought in contact therewith, thereby insuring a close connection between the contact members 19 and 20.

95 The arms 16 and 21, and the contact members 19 and 20 form a switch which is adapted to be actuated by the cam 15 to alternately make and break the circuit to the lights 22, thereby causing the latter to flash intermittently. The arm 21 is connected to one pole of the battery B by means of a conductor a, while the arm 16 is connected to the other pole of the battery B by means of a conductor b, to which the lights 22 are connected; the conductors a and b forming the lighting circuit which is in parallel with 100 the motor circuit.

105 The current for operating the motor 7 is delivered thereto from the battery B by means of the conductors a and b; the conductor b connecting with a normally open 110

switch for breaking the circuit to the motor 7. This switch is here shown as consisting of a pair of spaced spring contact members 26 and 26', and an arm 27 pivoted at 28, carrying a contact piece 29 which is adapted to form an electrical connection between the contact members 26 and 26' when the arm 27 is swung, as will be later described, to throw the contact piece 29 into contact with the spring members 26 and 26'.

10 The arm 27 is normally retained in such position as to dispose the contact piece 29 out of engagement with the spring contact members 26 and 26' by means of a spring 30, which holds the arm 27 against a stop 31 for preventing its outward movement. The arm 27 is designed to be actuated to complete the circuit through members 26 and 26' and thereby throw the motor 7 into 15 operation by means of a magnet 32 having a core so arranged that when the magnet is energized the arm 27 will be rocked on its pivot 28 in opposition to the spring 30, thereby moving the contact piece 29 into engagement with the spring members 26 and 26'.

One terminal of the magnet 32 connects with a conductor *e*, while the other terminal connects with a conductor *f* leading 30 to one terminal of the battery B. The conductor *e* leads to one side of a normally open switch 33, the other side of which connects with a conductor *g* leading to the other terminal of the battery B.

35 The switch 33 is designed to be so disposed in relation to the door, window, or other closure as to be operated by the opening thereof to complete a circuit from the battery B through conductor *f*, magnet 32, conductor *e*, switch 33, and conductor *g*, and thereby energize the magnet 32. Any number of switches 33 may be disposed between the conductors *e* and *g*, and they may be positioned at any convenient point, and may 40 be of any suitable construction.

Means are provided for automatically locking the arm 27 in its innermost circuit-making position so that a continuous circuit through the motor 7 will take place after 50 the switch 33 is thrown out. This means consists of a horizontally disposed arm 34 pivoted at 35 on the outer end of which an upwardly extending flange 36 is formed, which flange is adapted to engage the lower 55 end of the arm 27 when the latter is in its innermost position, as will presently be described. A spring 37 normally retains the arm 34 in its uppermost position; an outwardly-extending flange 38 on the flange 36 60 normally contacting the lower end of the arm 27 when the latter is in its outermost position to limit the upward movement of the arm 34. This arm 34 is designed to be moved in a downward direction by means 65 of a magnet 39, the core of which, when en-

ergized, acts to move the arm 34 downward in opposition to the spring 37. One terminal of the magnet 39 connects with the conductor *b* leading to one pole of the battery B by means of a conductor *h*; the other terminal of the magnet 39 being connected to the conductor *g* by means of a conductor *i*. The conductor *i* is normally broken by means of a switch 40 disposed at any convenient point.

70 In the operation of the invention, when any one of the switches 33 is operated by the opening of the closure to which it is attached, the magnet 32 becomes energized, thereby attracting the arm 27 and moving it 80 so as to dispose the contacting piece 29 in engagement with the contact members 26 and 26', thereby completing a circuit from the battery B through the conductors *a* and *b* to the motor 7, setting the latter in operation. 85

The arm 27 on being moved to its innermost position, as indicated by dotted lines in Fig. 1, is locked in this position by means of the arm 34, which is moved upward by 90 the action of the spring 37 when the lower end of the arm 27 passes beyond the inner face of the flange 36; the flange 36 preventing the backward movement of the arm 27 when the magnet 32 is deenergized.

95 The motor 7 on being set in motion drives the crank shaft 2 by means of the wheels 3 and 5 and the chain or belt 4. The crank shaft 2 on rotating actuates the bellows 9 by means of the pitman rods 8 in such manner as to pump a current of air through the passage 12 and pipe 13, out through the whistle 14, thereby sounding the latter.

100 It will be seen that the whistle 14 will be blown continuously as long as the motor 7 is in operation. It may, however, be blown intermittently by employing a single bellows 9 instead of a series, as shown. The crank shaft 2 on rotating causes the cam 15 to actuate the arm 16 and intermittently throw 105 the contact member 19 in and out of engagement with the contact member 21, thereby causing a current to intermittently flow through the lamp circuit *a*—*b* to repeatedly flash the lights 22.

110 From the foregoing it will be seen that as long as the contact piece 29 closes the circuit between the contact members 26 and 26', the motor 7 will be operated by the current from the battery B, thereby sounding the 115 whistle 14 and lighting the lights 22. When it is desired to stop the motor 7 and restore the parts to their normal position, the switch 40 in the conductor *i* is closed, thereby completing a circuit from the battery B through 120 the conductors *f* and *h*, magnet 39, conductor *i*, and conductor *g*, energizing the magnet 39 and causing it to attract the arm 34 125 and move the latter in a downward direction in opposition to the spring 37. The arm 130

34 in moving downward moves the flange 36 below the lower end of the arm 27, whereupon the spring 30 will act to move arm 27 to its normal position, as shown in full lines 5 in Fig. 1, thereby withdrawing the contact piece 29 from between the contact members 26 and 26', thus breaking the circuit from the battery B to the motor 7. The switch 40 is then opened to break the flow of current 10 through the magnet 39, thereby deenergizing the latter and allowing the spring 37 to restore the arm 34 in its normal position with the flange 38 abutting against the lower end of the arm 27.

15 It is manifest that any means for creating a current of air by the rotation of a crank shaft may be employed if desired, and that any switch mechanism for controlling the lights 22 from the motor 7 may be used.

20 The battery B may be disposed in the case or cabinet A thus making the apparatus self contained; it being obvious however, that any suitable source of electric supply may be employed as the occasion may require.

25 By arranging the lights 22 in parallel with the motor 7, the current thereto will be cut off when the switch 27 is thrown out to stop the motor, thus preventing the light from burning in event the cam 15 stops in

such position as to hold the switch members 30 19 and 20 in contact.

Having thus described my invention, what I claim and desire to secure by Letters Patent, is—

In an alarm apparatus, the combination 35 of electrically controlled signals including an audible signal and a visual signal, electrically operated means to continuously produce air pressure to operate said audible signal, said means comprising an outer casing, 40 an inner wall concentrically located within said outer casing to provide a passageway therebetween, a plurality of pressure producing devices having valve connections with said passageway, means centrally located within the casing for actuating said device, and means controlled by said actuating means for intermittently operating said 45 visual signal, all of said parts being automatically set into operation by the opening 50 of a closure.

In testimony whereof I have hereunto set my hand in the presence of two subscribing witnesses.

LEON A. NORTHRUP.
